LASER MATERIAL CUTTER

Peter P. Klepa and Thomas J. Hermann, Los Angeles,
Calif., assignors to Hughes Aircraft Company, Culver
City, Calif.

Filed Jan. 10, 1972, Ser. No. 216,889

Term of patent 14 years

Int. Cl. D15—09

U.S. Cl. D55—1 A

Fig. 4.

Fig. 5.

FIG. 1 is a perspective view of a laser material cutter showing the new design;

FIG. 2 is a front elevational view thereof, at a reduced scale;

FIG. 3 is a rear elevational view thereof, at a reduced scale;

FIG. 4 is a right side view thereof; and

FIG. 5 is a top plan view thereof.

The partial shading on various surfaces is understood to represent the appearance of the entire surface so shown.

We claim:

The ornamental design for a laser material cutter, substantially as shown and described.
